UNITED STATES PATENT OFFICE

146,526

DESIGN FOR A HOLDER FOR TABLEWARE
OR OTHER ARTICLES

Edward L. Shaw, Brookline, Mass., assignor to Hawkridge Brothers Company, Boston, Mass., a corporation of Massachusetts

Application August 14, 1945, Serial No. 121,427

Term of patent 3½ years

(Cl. D44—24)

To all whom it may concern:

Be it known that I, Edward L. Shaw, a citizen of the United States, residing at Brookline, in the county of Norfolk and Commonwealth of Massachusetts, have invented a new, original, and ornamental Design for a Holder for Tableware or Other Articles, of which the following is a specification, reference being had to the accompanying drawing, forming a part thereof, in which the figure is a view in perspective of a holder for tableware or other articles, showing my new design.

I claim:

The ornamental design for a holder for tableware or other articles, substantially as shown.

EDWARD L. SHAW.
